UNITED STATES PATENT OFFICE.

JAMES R. RICKETTS, OF HENDERSON'S CROSS ROADS, TENNESSEE, ASSIGNOR
OF ONE-HALF TO JAMES H. WHITE, OF SAME PLACE.

WATER-ENGINE.

SPECIFICATION forming part of Letters Patent No. 463,583, dated November 17, 1891.

Application filed May 11, 1891. Serial No. 392,355. (No model.)

To all whom it may concern:

Be it known that I, JAMES R. RICKETTS, a citizen of the United States, residing at Henderson's Cross Roads, in the county of Wilson, 5 State of Tennessee, have invented certain new and useful Improvements in Water-Engines, of which the following is a specification, reference being had therein to the accompanying drawings.

10 This invention relates to certain new and useful improvements in water-engines; and it has for its objects, among others, to provide an improved device of this character which shall be capable of being operated with a small 15 force of water and yet produce sufficient power for the purposes for which it is intended. I provide a walking-beam to which the boxes are pivoted, and a second walking-beam receiving motion from the primary walking-beam and adapted to disengage the boxes from 20 their catches. The parts are so arranged as to automatically operate, the valves being automatically opened and closed in the alternate movements of the walking-beam and 25 boxes.

Other objects and advantages of the invention will hereinafter appear, and the novel features thereof will be specifically defined by the appended claims.

30 The invention is clearly illustrated in the accompanying drawings, which, with the letters of reference marked thereon, form a part of this specification, and in which—

Figure 1 is a side elevation of my improved 35 device with parts broken away. Fig. 2 is a top plan with a portion of the water-receptacle broken away.

Like letters of reference indicate like parts in both views.

40 Referring now to the details of the drawings by letter, A designates a suitable foundation or base from which rise the uprights A' A' and A², the former serving as a support for the water-receptacle B, which may be of any desired capacity and shape, but preferably rectangular, as shown. It is designed to be arranged adjacent to a stream of running water, or it may be operated from any other source of supply, as a city water-supply, being arranged in any case so that the water

will flow readily into the receptacle from a slight elevation.

Pivoted to an upright b on the side of the receptacle B is a horizontal beam C, to each end of which is pivotally secured a vertical bar or link C', which at its lower end is pivotally connected to a valve D, pivoted at one end, as at d, within the receptacle and its other end adapted to close or disclose the discharge-opening c in the side wall of the receptacle, a suitable spout b' being provided to throw the water which passes through the said opening into the boxes hereinafter described. A suitable guide, as e, may be provided within the receptacle to guide the valve 65 in its vertical movements, although this is not absolutely necessary.

Pivoted at its center to the upright A² is the main walking-beam D', to each end of which is pivoted a box or receptacle E, provided upon its inner end with a horizontal lip f, which is adapted to be engaged and held by the pivoted latch or catch F, which is pivoted to the said walking-beam and its free end connected to the upright A² by a cord or chain g, as shown. Each box is also provided with a rod h, which is adapted to engage a lateral pin i on the walking-beam to limit its movement when the lip is disengaged from the latch. The inner upper ends of the boxes 80 are connected with the base or foundation A by means of cords or chains j, as shown. The shaft of this walking-beam constitutes the power-shaft from which the power may be conveyed in any suitable manner to the desired point.

Pivoted to the upright A² is a secondary walking-beam G, which is connected upon opposite sides of its pivot with the beam C by cords or chains k, the preferred manner of 90 connection being shown in Fig. 2, where I have shown lateral pins l projecting from the beam C, and to which the said cords or chains are attached, thus bringing the connection outside of the water-receptacle.

The walking-beam G is provided at each end with a horizontal shoe or plate m, against which the outer end of the box engages when it is tilted.

The operation will be readily understood 100

from the above description when taken in connection with the annexed drawings. The water flows into the receptacle B and out through whichever opening may be uncovered 5 and through the spout into the box E, which is at this time elevated, as shown in Fig. 1, the said box being held in its upright position by the latch engaging its lip, as shown. As the box becomes full, it descends, and as it descends it pulls upon the cord or chain g, which disengages the catch or latch from the lip and the box tilts into the position shown at the right of Fig. 1, the stop limiting its movement, and as it tips it engages the shoe or plate m on the walking-beam G and depresses that end, thus pulling down the valve at that end of the receptacle and closing the opening, and at the same time opening the other opening by its valve being raised, so that the water will flow through the said opening into the other box, which has been raised as the other box descended. As the box ascends, the cord or chain attached to that latch or catch is loosened and the latch falls into engagement 25 with the lip m on the box and holds it in its upright position:

The device is simple, cheap of construction, requires but little power, and is not liable to get out of order, and requires no attention on 30 the part of an operator or attendant.

What I claim as new is—

1. The combination, with the water-receptacle having openings and the pivoted alternately-operating valves, of the walking-beam, the tilting boxes pivoted thereto and having

40
lips, the pivoted latches engaging the said lips, the cords connected to the latches, and the secondary walking-beam connected with the valve-beam and adapted to serve as set forth.

2. The combination, with the walking-beam and the pivoted boxes thereon, of the pivoted latches on the walking-beam, the cords connected to the latches, and the rods on the boxes engaging fixed stops on the beam, as 45 set forth.

3. The combination, with the pivoted walking-beam provided with lateral stop-pins, of the boxes pivoted to the beam and provided with lips, the stop-rods on the boxes, the cords 50 connecting the latches with some fixed part, and the latches pivoted on the beam, substantially as and for the purpose specified.

4. The combination, with the water-receptacle having discharge-opening near each end, 55 of the walking-beam provided with pivoted boxes and latches, the cords connected with the boxes and latches, the beam carrying the pivoted valves, the secondary walking-beam, with its ends arranged in the path of the 60 boxes, and the cords connecting the secondary beam with the valve-beam, substantially as shown and described.

In testimony whereof I affix my signature in presence of two witnesses.

JAMES R. RICKETTS.
